UNITED STATES PATENT OFFICE.

CHARLES P. WATSON, OF BIG PINE, CALIFORNIA.

PERCUSSION FUSE.

Application filed March 9, 1921, Serial No. 451,002.

To all whom it may concern:

Be it known that I, CHARLES P. WATSON, a citizen of the United States, residing at Big Pine, in the county of Inyo and State of California, have invented new and useful Improvements in Percussion Fuses, of which the following is a specification.

My invention relates to fuses such as are used in connection with ordnance projectiles, and are adapted to be fired upon impact of the projectile. The preferred form and construction of my invention is illustrated in the accompanying drawings and will be hereinafter described.

In such drawings, Figure 1 is a central, longitudinal section of the fuse.

Figure 2 is a longitudinal section taken on the broken line II, II of Figure 1.

Figures 3, 4 and 5 are cross sectional views taken respectively on the lines III, III, IV, IV and V, V of Fig. 1.

Figure 6 is a broken sectional view illustrating a modification.

In the drawings the casing of the fuse is designated 2. This is preferably formed from cylindrical stock metal, cut to a proper length and bored out internally to form a forward chamber 8, in which is located the booster charge of the fuse, and a rear chamber 23 in which are located the several operative and functioning elements of the fuse, which will be later described. The chamber 23 is divided by a partition 12, having screw-threaded engagement with the casing 2, into two parts, in the rear one of which is located a plunger 20 carrying a firing pin 21. The rear end of the chamber 23 is left open, and its wall near the rear end is internally screw-threaded as indicated at 3, to receive a closing plug 6. This plug is provided with a flange 7, adapted to abut against and extend over the rear edge of the casing 2, when the plug is screwed tightly into place, and constituting the rear end flange of the fuse considered as a whole. The fuse casing is externally screw-threaded as indicated at 4 in proximity to the flange 7, such screw threads serving as the means for uniting the fuse with the shell or casing of the projectile. The inner end of the closing plug 6 is formed with a cone shaped recess to receive and fit the correspondingly shaped end 24 of the plunger 20. The fuse casing 2, opposite the recessed end of the plug 6, is weakened, preferably by an external circumferential groove 5. It sometimes hap-

pens that the case of the fuse is deformed, by reason of side impact of the projectile, with the result that the plunger, carrying the firing pin, becomes jammed or pinched and hence inoperative, rendering it impossible for the fuse to function and making the shell dead. By weakening the casing of the fuse as described, any giving way or deforming of the fuse due to side impact will naturally take place at the weakened zone thereof—where the circumferential groove 5 is formed—and as this is opposite the conical end of the plunger, the deforming of the fuse case will act to push forward the plunger 20, either causing the fuse to function immediately or else moving the plunger into a part of the chamber 23 that remains in shape and undeformed, where it will be in condition to function immediately upon end-on impact of the projectile.

By constructing the fuse casing in the manner described I can use for the major part thereof stock material of the diameter 80 of the body of the fuse, and at the same time provide the fuse with an end flange 7. Heretofore, it has been customary in manufacturing casings for fuses to use stock material of a diameter equal to the diameter 85 of the end flange and to cut this down to the size which the fuse body is to have, with the result that much machine work was necessary in manufacturing such fuses and considerable waste of material resulted. By 90 the use of my invention, however, the only part of the fuse that is made from stock material of the diameter of the flange 7 is the short portion constituting the closing plug 6. 95

The booster charge carried by the fuse is loaded into the chamber 8, at its inner end. The partition 12 is formed with a tubular extension 14, the end of which enters and tightly closes the opening 39 through the barrier 38 that separates the booster chamber 8 from the chamber in which is located the firing mechanism and the primer. The end of the extension 14 enters the opening 39, and when properly seated therein and held in place by the engagement of the partition 12 with the walls of the fuse casing or body, becomes, in effect, a part of the said barrier partition separating the chambers 8 and 23, and this barrier is of sufficient strength to resist the effects of any accidental explosion of the primer, or that part 100 105 110

of the detonating train located in the chamber 23, and prevents such accidental explosion from setting off the booster charge. Through the partition 12 and extending into the tubular part 14 is a chamber for the primer and a part of the detonating train of the fuse. The said train consists preferably of a charge of compressed fulminate 16 behind which is a delay pellet 17, separating the compressed fulminate from the primer or percussion cap 18 that is intended to be acted upon directly by the firing pin 21. The delay pellet 17 is formed of an explosive of such nature that it acts relatively slowly, serving to insure a slight delay between the time the percussion cap is ignited and the moment the compressed mercury charge is fired, thus giving the projectile time to pass through armor before it is ruptured. In the forward portion of the tubular part 14 is formed a passage 15 into which is loaded a train of explosive constituting part of the detonating train and preferably formed of tetryl pellets or an equivalent high explosive. In order to get a detonation of the projectile of high order, it is important that each successive charge as it is ignited should be violently detonated, and I have devised several improvements to increase the intensity of the successive detonations. The passage 15 does not extend directly through to the end of the projection 14. It is rather divided, continuing as diverging passages, as indicated in Fig. 1. Into these passages are seated the ends of a detonating cord, that is a piece of fuse cord 13 carrying high explosive, the intermediate part of the fuse cord 13 being in the form of a loop within the chamber 8 and in immediate proximity to the booster charge. The detonation of the explosive within the channel 15 acts to ignite simultaneously the ends of the fuse cord 13. The detonating waves incident to the combustion of this fuse cord, traveling at an exceedingly high velocity, meet at a point approximately the center of the fuse cord and in immediate proximity to the booster charge. The effect of this meeting of the detonating waves, approaching each other from opposite directions, is to very greatly intensify the action of the fuse, as compared with what it would be if, for instance, the perforation 15 extended directly and entirely through the part 14, or if two independent pieces of detonating fuse cord were inserted in the diverging passages at the end of the channel 15, and such detonating fuses terminated in contact with the booster charge but separate from each other. In order to make a fuse such as I have described safe under all conditions, except when the projectile carrying it is fired from a gun, I transversely perforate the tubular extension 14, as indicated at 26, the perforation 65 26 intersecting the longitudinal perforation

15 and being preferably of larger diameter than the latter. In the perforation 26 is mounted a rotatory bolt 27 that is formed at one end with an arm 28 extending therefrom at substantially right angles, the end of the bolt opposite that carrying the arm 28 having a head 29 that may conveniently be formed by a short, removable, large headed screw. A spring 30 is interposed between the bolt 27 and the tubular extension 14 and acts as a means to hold the bolt normally in safety position. The spring illustrated is constructed and arranged so that it acts both as an expansion spring and as a torsion spring. It is a coiled spring surrounding the stem of the bolt being preferably partly seated in a recess 32 formed therefor in the part 14, and is at one end connected with the bolt, and at its other end with the part 14. The expansive action of the spring operates to move the bolt longitudinally in a direction to bring the arm 28 against the tubular extension 14, which latter is provided with a shallow recess 31 in which the end of the arm rests, as represented in Fig. 1, being thereby held in the position indicated. The torsional action of the spring operates to rotate the bolt in such a way that the arm 28 thereof lies parallel with the tubular extension 14 and seated in the recess 31, as represented in Fig. 1. There is a diametric perforation 33 through the bolt 27, this being so located that when the bolt is in the position indicated in Fig. 1 and in full lines in Fig. 2 it does not register with the longitudinal perforation 14 through the extension 15, but rather lies transverse thereto and somewhat to one side thereof. When, however, the bolt is turned in its seat 26 into the position represented in dotted lines in Fig. 2, the perforations 33 and 15 register. Thus it will be seen that when the bolt occupies the position represented in Fig. 1, it operates as a cut-off in the passage between the booster chamber 8 and the chamber in which is located the primer, so that if there should be a premature or accidental explosion of the primer the detonating effects thereby produced will not be communicated to the booster charge and through it to the bursting charge of the shell, but will be confined to the chamber 23, the walls of which are sufficiently strong to withstand the pressures incident to such an accidental explosion. In order that the pressures incident to any such accidental explosion may be dissipated as far as possible the partition 12 is perforated, as indicated at 35, permitting the gases that would be generated to expand into the chamber 23 on both sides of the partition.

I refer to the bolt 27 as rotatory though it is permitted to turn upon its longitudinal central axis, in functioning as has been described, only a partial revolution.

The plunger 20 carries the firing pin. This may be of any preferred style to insure safety. I prefer that it should be moved into armed or firing position by a pair of centrifugally operated blocks, the construction and arrangement of the firing pin and the centrifugal operating blocks being similar to those illustrated in my Patent 1,197,414 of September 5, 1916. These, being 5 fully described in said patent, need not be described in detail here.

A spring 22 is interposed between the plunger and the base of the recess in which the plunger is located and acts to hold the 10 former against partition 12 under normal conditions, to permit it to set back when the shell is fired from a gun.

The operation of the fuse is as follows: The parts of the fuse are normally in the 20 positions indicated in Figs. 1 and 2; the firing pin being retracted and within the body of the plunger, its pointed end being below the forward face thereof so that, should the plunger move forward, the primer will not 25 be acted upon; and the bolt 27, resting in safety position, will cut off communication between the chamber where the primer is located and that in which the booster charge is placed. Upon the shell being fired, centrifugal force, developed by the rotation of the 30 shell in its flight, causes the firing pin to become armed, in the manner described in my aforesaid patent. Further description 35 of this is therefore unnecessary.

The operation of the safety bolt 27 is as follows: During the movement of the shell through the bore of the gun and for some 40 distance beyond the muzzle thereof, the shell is being violently accelerated, with the result that inertia, acting upon the free eccentrically disposed arm 28 of the bolt, causes it to lie in the line of the flight of the shell that is parallel with the projection 14 and as represented in Fig. 2. As soon, however, 45 as acceleration ceases, any tendency for the arm to remain in this position, due to inertia, ceases. Centrifugal force, generated by the rotation of the projectile, acts upon 50 the movable bolt 27, and the disposition of the weight of the parts thereof is such that this force tends to move the bolt longitudinally in its seat in a direction to carry the arm 28 away from the part 14, thus releasing 55 it from the recess 31 and compressing the spring 30. Centrifugal force now, acting on the arm 28, causes the bolt to be rotated into the position indicated in dotted lines in Fig. 2 with the arm sticking out or projecting at 60 right angles to the axis of the line of flight of the shell. These movements of the bolt, due to the action of centrifugal force thereon—first longitudinal movement freeing the arm 28 from the recess 31, and then rotative 65 movement causing the arm to stand trans-

verse to the axis of flight—brings the perforation 33 into line with the perforation 15, thus removing the barrier that normally rendered the fuse safe against explosion due to the firing of the primer.

It will be seen that not only is a fuse, constructed according to my present invention and in the manner described and illustrated in the accompanying drawings, safe under normal conditions, but it also possesses bore 70 safety, because the disposition of the weights of the several parts of the bolt 27 are such that the force of inertia, acting upon the eccentric arm of the bolt while the shell is within the bore of the gun and while its 80 speed of flight is being accelerated, is stronger than is the centrifugal force due to the rotation of the shell, so that the latter can not become effective to arm the fuse, by removing the barrier cutting off the 85 booster chamber, until after the projectile ceases to accelerate in speed, which does not take place until the projectile has progressed some distance beyond the muzzle of the gun.

It will be understood that a turret bolt 27, 90 arranged similarly to that shown in the drawing except that it is not free to move longitudinally in its seat, would be effective and operate successfully as a safety cut-off 95 between the chamber containing the primer and that in which is located the booster charge, but the arrangement shown has certain advantages, as it gives a double element of safety.

Such a turret bolt as that just referred to 100 is represented in Fig. 6. In this view the eccentric arm 28 of the turret bolt is positively held in normal safety position by a locking bolt 34, one end of which is seated in a recess 37 in such arm and its other end 105 in a recess 35 formed in the partition 12. A split elastic ring 36 surrounding the bolt tends to hold it in normal locking position but yields upon the set back of the bolt at the instant of firing the shell permitting the 110 bolt to enter the recess 35 where it is held by the spring 36, leaving the turret bolt free to function as has been described.

Having described my invention, what I 115 claim is:—

1. A fuse for ordnance projectiles, comprising a casing in which is formed a chamber, a movable plunger located in said chamber adapted to function upon impact of the shell to fire the fuse, and the outer wall 120 of the fuse casing enclosing the chamber therein being weakened toward the rear of the chamber, whereby should the fuse be deformed by reason of side impact of the projectile in flight, the casing will yield at the weakened part, and such weakening will be in rear of the plunger so as not to interfere with its functioning.

2. A fuse for ordnance projectiles comprising a casing in which is located a mov- 125

able plunger carrying a firing pin, the plunger being in part cone shaped, and the fuse casing being circumferentially weakened in the portion lying outside the cone 5 shaped part of the plunger, whereby should the fuse deform by reason of side impact of the projectile its casing will give way at the said weakened part and such giving way will cause the wall of the casing to act on 10 the conical portion of the plunger to move it in the direction for firing the fuse.

3. A fuse for ordnance projectiles, comprising a casing chambered to receive and carry in one part a booster charge of explosive, and in another mechanism for firing the charge, a barrier separating the said charge and mechanism chambers, through which is formed a passage that divides into two separated parts toward the chamber for the 20 booster charge, a detonating fuse cord located in the said passage and extending therefrom in the form of a loop into proximity to the charge to be detonated, the end portions of the cord being carried respectively 25 through the two separated parts of the passage through the barrier and then brought together in the undivided part of such passage while the loop extends beyond the barrier, and means for simultaneously igniting 30 the said portions of the fuse cord that are brought together, whereby detonating waves due to the combustion of the said cord, starting from the place of ignition thereof, conducted, through the separated passages in 35 the barrier, and meeting in the looped portion of the cord outside the barrier, cause the action of the fuse to be intensified.

4. In a fuse for ordnance projectiles, a casing chambered to receive and carry in one 40 part a booster charge of explosive and in another part mechanism for firing the said charge, a barrier interposed between the explosive charge and the firing means, and an oscillating turret bolt adapted when in normal 45 position to serve as a safety cut-off in the said barrier, the turret bolt being arranged to be oscillated by the action of centrifugal force due to the rotation of the projectile in flight and to complete the connection 50 between the two chamber parts of the fuse.

5. In a fuse for ordnance projectiles, a casing chambered to receive and carry in one part a booster charge of explosive and in another part mechanism for firing the charge, a tubular connection interposed between the explosive charge and the firing means and an oscillating turret bolt supported transversely in the said tubular connection 55 and serving as a safety cut-off between the booster charge and the means for firing it, the turret bolt having an arm normally lying outside the tubular connection, and the bolt being arranged when oscillated out 60 of normal position to establish connection 65

between the booster charge and the firing means, the force of inertia, due to acceleration of the speed of flight of the projectile carrying the fuse, acting on the arm of the turret bolt to hold it in safety position, and 70 centrifugal force, due to the rotation of the projectile in flight, acting on the arm oscillating the turret bolt.

6. In a fuse for ordnance projectiles, a chambered casing carrying a booster charge 75 and means for firing such charge, a tubular connection interposed between the charge and its firing means, an oscillating turret bolt adapted to serve as a safety cut-off in the said tubular connection, the turret bolt 80 being arranged to be oscillated by the action of centrifugal force due to the rotation of the projectile in flight to arm the fuse, and a spring acting on the said turret bolt tending to hold it in safety cut-off position, 85 but arranged to yield when the turret bolt is subjected to centrifugal force and permit the fuse to be armed.

7. In a fuse for ordnance projectiles, a casing chambered to receive and carry a booster 90 charge and means for firing such charge, a tubular connection interposed between the charge and the firing means, an oscillating turret bolt transversely supported in the said tubular connection and arranged to serve as 95 a safety cut-off to interrupt the tubular connection, the turret bolt being supported so as to be movable to a limited extent longitudinally, and a combined expansion and torsion spring acting on the said bolt for holding it 100 in safety position, the bolt having an eccentrically disposed part adapted to be acted upon by centrifugal force when the fuse is in rotation during the flight of the projectile, such centrifugal force tending to move 105 the turret bolt longitudinally in its seat against the action of the said spring, and also tending to cause it to oscillate, also against the action of the said spring, the movements of the turret bolt operating to 110 arm the fuse, putting the firing means into communication with the booster charge.

8. In a fuse, the combination of a rotatory part having an eccentric arm at approximately right angles thereto and adapted to occupy either a safety or an armed position, whereby inertia acting on the eccentric arm due to the acceleration of a shell carrying the fuse tends to hold the part in safety position, and centrifugal force due to the rotation of the shell in flight acting on the arm tends to move the part to armed position. 115

9. The combination stated in claim 8, including also means that maintain the said rotatory part in safety position under normal conditions. 120

10. In a fuse the combination of a rotatory cylindrical part adapted to occupy either a safety or an armed position, the said part having an eccentric extension 125 130

whereby inertia due to the acceleration of a shell carrying the fuse tends to hold the part in safety position, and centrifugal force due to the rotation of the shell in flight 5 tends to rotate the part about its longitudinal axis to armed position.

11. In a fuse, the combination of a rotatory cylindrical part transversely supported relative to the axis of the fuse and adapted 10 to occupy either a safety or an armed position, the said part having an eccentric extension whereby inertia due to the acceleration of a shell carrying the fuse tends to hold the part in safety position, and centrifugal force due to the rotation of the shell in flight tends to rotate the part about 15 its longitudinal axis to armed position.

12. The combination stated in claim 10, including also means that maintain the 20 rotatory cylindrical part in safety position under normal conditions.

13. In a fuse, the combination of a rotatory cylindrical part transversely supported relative to the axis of the fuse and adapted 25 to occupy either a safety or an armed position, the said part having an eccentric extension whereby inertia due to the acceleration of a shell carrying the fuse tends to hold the part in safety position, and centrifugal force due to the rotation of the shell in flight tends to move the part laterally and to rotate it about its longitudinal 30 axis to armed position.

14. The combination stated in claim 13, including also means that maintain the 35 rotatory cylindrical part in safety position under normal conditions.

15. A high explosive detonating fuse formed with a chamber to receive a detonating charge and another chamber in which 40 are located the primer and the movable functioning parts that fire the primer, these elements being connected by a channel of communication, a rotatory cylindrical bolt 45 supported so as to intercept the said channel and constitute a closing barrier between the chambers when moved to safety position, the bolt being formed with a passage arranged to register with and constitute part 50 of the channel of communication when the bolt is rotated to armed position.

16. The combination stated in claim 15, including also means for holding the said 55 bolt in a predetermined position.

17. In a fuse, a rotatory part turning 60 about an axis that is transverse to the longitudinal axis of the fuse and the shell that carries it, arranged to occupy either a safety or an armed position, means for holding the said rotatory part normally in the safety position but arranged to be operated to release the rotatory part upon the shell being fired from a gun, and a spring acting upon 65 the rotatory part and tending to move it to safety position.

18. In a fuse, a functioning element comprising a transverse rotatory part arranged to occupy either a safety or an armed position, a coiled spring surrounding the said rotatory part and having one of its ends 70 secured thereto and the other end secured to a non-rotating part of the fuse, the spring being arranged to act on the said rotatory part to move it to safety position, and means to normally hold the part in safety position 75 arranged to be moved to release the part when the shell is fired from a gun.

19. In a high explosive detonating fuse formed with a chamber to receive a booster charge and another chamber in which are located the primer and the movable functioning parts that fire the primer, these chambers being connected by a channel of communication, a rotatory bolt supported 80 so as to intercept the said channel and to constitute a closing barrier between the chambers when moved to safety position, the bolt having a diametric passage through it arranged to register with and constitute part of the channel of communication when the bolt is rotated to assume armed position.

20. In a detonating fuse, a fuse body having a chamber in which is located the booster charge and another chamber separated therefrom in which is located the primer and the firing means, and a channel of communication between the said chambers, means arranged to cut off the said channel of communication when occupying 95 a safety position and to leave the same open when occupying an armed position, a charge of detonating explosive for the booster charge to be ignited from the primer chamber when the said channel of communication is open, 100 arranged in front of the said cut-off means, and means to direct and intensify the effects of the said detonating explosive where it directly acts upon the booster charge.

21. In a detonating fuse, a fuse body 110 having a chamber in which is located the booster charge and another chamber separated therefrom in which is located the primer and the firing means, and a channel of communication between the said chambers, means arranged to cut off the said channel of communication when occupying a safety position and to leave the same open when occupying an armed position, a detonating train of high explosive material 115 between the primer and the booster charge, which train is divided by the said cut-off means, the portion of such explosive train to the rear of the cut-off being surrounded by an expansion chamber, and the portion in front of the cut-off being arranged so that its explosive effect is directed to intensify 120 its action on the booster charge.
